UNITED STATES PATENT OFFICE.

ALBERT BALL, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

MINING-MACHINE.

1,205,076.

Specification of Letters Patent. Patented Nov. 14, 1916.

Application filed November 24, 1908. Serial No. 464,320.

To all whom it may concern:

Be it known that I, ALBERT BALL, a citizen of the United States, and residing at Claremont, county of Sullivan, and State 5 of New Hampshire, have invented an Improvement in Mining-Machines, of which the following description, in connection with the accompanying drawings, in a specification, like letters on the drawings represent- 10 ing like parts.

My invention relates to mining machines, being more particularly intended to provide improved means for feeding and guiding a mining machine while performing the cutting operation.

My invention will be best understood by reference to the following description when taken in connection with the accompanying illustration of one specific embodiment 20 thereof, while its scope will be more particularly pointed out in the appended claims.

In the drawings: Figure 1 shows in plan, partially broken away, a mining machine embodying one form of my invention; Fig. 2 shows the same mining machine in side elevation and on a reduced scale, the forward end of the cutter bar being broken away; Fig. 3 is a section in elevation on the line 3—3 in Fig. 1 showing a device for 25 ratcheting one of the winding drums to adjustably take up or let out the trailing cable; Fig. 4 is a central sectional plan on the line 4—4 in Fig. 3; Fig. 5 is a similar sectional plan showing the other winding drum; Fig. 6 is a section in elevation showing the brake or retarding device for one 35 of the winding drums; Fig. 7 is a detail in sectional elevation showing the locking pawl for leading winding drum, and Figs. 40 8, 9 and 10 are diagrams showing the mining machine of Fig. 1 as arranged for the starting cut, main cut and loading movement respectively.

Referring to the drawings and to the embodiment of my invention which I have there disclosed, for the sake of illustrating one concrete form of my invention a mining machine of the well-known cutter-chain type having the body or main frame 1 with the 45 cutter bar 2 projecting therefrom and adapted to undercut the wall of the mine with a horizontal kerf as the machine is moved transversely relative to the direction of cut-

ter bar length or in the direction shown by the arrow in Fig. 1.

The cutter bar, as usual, carries a suitable cutter chain 3 driven from the driving sprocket wheel 4. The latter is mounted on the driving shaft 5, to which is secured the large driven gear 6 driven by the pinion 7 on the shaft 8 of the upright electric motor 9 on the frame of the machine. These power-transmission parts are indicated by dotted lines in Fig. 1 and their constructional details form no essential part of the present invention, but, herein, having reference to these as well as to certain other constructional features of the machine, I have, for illustration, shown my invention as applied to a machine of the general construction shown in the prior patent to Mitchell No. 656,414. While, for such purpose, any suitable construction may be employed, in the present machine, supporting means are provided upon and with which the machine is adapted to move along the mine and preferably, as in the Mitchell patent referred to, in the form of a bottom member or shoe 10 (Fig. 2) upon which the machine is adapted to slide, if desired, directly upon the bottom or floor of the mine.

In order to hold the cutter chain and the cutter bar in the desired relation against the work as the machine is fed along, guiding means are provided, the same consisting of 85 one or more ropes, cables or other flexible guiding members kept under tension and so associated with the machine that the cutter bar, as it travels, is held up to the work without the necessary use of rails or other 90 like guiding supports. In the illustrated form of my invention I have provided for this purpose flexible guiding means, herein in the form of a wire rope or cable presenting two portions or lengths 11 and 12, both 95 connected to a fixed support, one on the advancing side of the machine and the other on the receding thereof, and one connected to the machine adjacent its wall or cutting end and the other nearer the opposite end 100 thereof. These two lengths or portions preferably consist of two separate lengths each wound upon and unwound from suitable winding devices although other arrangements might be adopted within the 105 spirit of the invention.

As seen in Fig. 1 the leading cable 11 on the advancing side of the machine is wound about the winding drum 13 mounted to rotate about the horizontally and transversely disposed shaft 14, the said cable, during the lateral feeding movement of the machine, being connected to the latter about a fulcruming guide, which guide is in the form of a guide sheave 15 preferably mounted in substantially upright bearings on the advancing side of the machine and near the wall or cutting end thereof. On the other hand, the rear or drag line cable 12 is connected to the drag line drum 16, the latter mounted to rotate about the horizontally disposed shaft 17 suitably supported near the rear end of the machine, so that the cable, during the operation of the machine, is adapted to leave the machine on the receding side and near the outer end thereof or that end opposite the wall or cutting end. The two cable portions (as represented in Figs. 1 and 9) may, therefore, be arranged in two substantially parallel lengths and, when under tension, with the cutter chain in position against the work, will serve to hold the cutter bar against the work and in a position which can be regulated by adjusting the drag line cable 12 to swing the machine more or less about the guiding sheave 15 as a fulcrum.

While the two cables 11 and 12 might be employed solely to guide the machine and hold the same in the desired relation to the work, other and independent means being employed positively to feed the machine, herein preferably I employ power-driven means to draw in one of the guide members while paying out the other, thereby to feed the machine at the same time it is guided. To this end both the winding drums 13 and 16 are connected to be driven in unison from the motor 9 so as to draw in one while equally paying out the other cable and to maintain the established tension on the two cables while causing the advance of the machine.

In the disclosed form of machine in order to drive the drums, the upright driving shaft 5 is provided with the driving pinion 18 meshing with the gear 19, the latter being connected to turn the smaller pinion 20 and the intermeshing gear 21, which latter is connected to turn the beveled gear 22. To drive the drum 13 the gear 22 has meshing therewith the beveled gear 23 fixed to the driving shaft 24, the latter (see Fig. 5) carrying at its end the driving pinion 25 meshing with an internal gear 26 carried by the inner face of the winding drum 13. Similarly, the drum 16 is driven from the bevel gear 27 meshing with the driving gear 22 and carried on the driving shaft 28, (Fig. 4), which latter is provided with the driving gear 29 meshing with the internal gear 30 on

the driving drum 16. By this means both drums are driven at the same speed from the motor 9 and in a suitable direction to pay out the cable 12 while taking in the cable 11, or vice versa.

Referring to Fig. 9, the operation of the machine in effecting the lateral or main cut will be clear. As the machine cuts it is advanced by the winding in of the cable 11, which latter extends to a fixed support such as the anchor bar 68 fixed at the end of the coal face. The cable 12 which extends to a fixed support 59 is paid out to an equal extent so that the same cable tension is constantly maintained. The machine, therefore, as it travels, is held in and against the work, the cutters acting to draw the machine in and the trailing cable tending to swing the cutter bar forward about the fulcruming guide sheave 15 and hold the cutters against the coal.

In order to disconnect either or both winding drums from the driving motor the transmission gearing for quickly winding in or unwinding the cables when the cut has been completed or for any other purpose, means are preferably provided for disconnecting either drum at will from the driving motor. Any suitable means may be provided for this purpose, but herein the shafts on which the drums are journaled are eccentrically mounted, so that each one may be moved out of engagement with its driving gear. For example, the drum 13 is mounted on an eccentric portion of the shaft 14 and the latter being journaled in the bracket 31 on the machine frame is provided with the hand lever 32 by which the shaft may be turned through 180° to permit the eccentric portion thereof to draw the internal gear 26 into or out of mesh with the driving gear 25. Similarly, the drum 16 is mounted on an eccentric portion of the shaft 17 and the latter, being rotatably held in the bracket 33, may be turned by the hand lever 34 to engage the internal gear 30 of the drum 16 with the pinion 29, or disengage the same therefrom. This permits either drum to be thrown out of engagement with the driving motor and the transmission gearing at will.

One difficulty following the use of cables and winding drums on machines of this nature, lies in the tendency of such cables to uncoil from the drums or the tendency of their coils to open or spread while on the drums, and thereby to become entangled, when the drum is suddenly freed for turning while its cable is still under tension. This may happen, for example, at the end of the cut when, with the cables still under tension, one or both drums may be disengaged from the transmission mechanism by turning its eccentric bearing shaft. Under such circumstances the drums tend suddenly to spin about and spread or unwind the

cable coils with consequent entanglement of the cable. To oppose the uncoiling tendency of the cables under these or other conditions, I preferably provide means, such for example, as the hood or casing 35 fixedly secured to the shaft 14 (see Fig. 5) and presenting to the coils when wound on the drum a peripheral wall 36 which lies closely adjacent the coils and acts to house them in so that 10 any tendency to loosen and spring away from the walls of the drum when the latter is suddenly freed is effectually prevented by the coils coming in contact with the inner walls of the casing. If the drum, therefore, 15 is suddenly disconnected from the driving gear with its cable under tension, even if the drum spins around, the coils cannot expand or open far enough to pass over one another or become entangled with each 20 other, but through the proximity of the bearing, are maintained in the same helical relations obtaining when they were first wound upon the drum. If desired, in order to better preserve the successive convolutions of the cables in their normal relation, the peripheral walls 36 of the hood may 25 not only be brought very close to the cable strands as shown, but the winding surface of the drum may be provided with helical 30 grooves to correspond to the cable coils, so that one coil cannot possibly crowd over the next adjacent one.

The hood 35 for the drum 13 is shown as entirely inclosing the drum, except where 35 exit of the cable is necessary, the drum being manually turned, when disconnected from the driving gear, for the purpose of quickly winding up the cable by means of the driving pinion 38 meshing with the internal gear 39, the latter formed on the interior of the drum 13, the said gear being turned by the removable hand crank 40 connected to the gear shaft 41. For the drum 16 there is also preferably provided a similar hood or casing 42, the latter, however, as shown, preferably leaving the inner end of the drum open and exposed, so that the latter may be turned adjustably to take up or let out the trailing cable by means of a 45 ratchet lever 43 to be more fully described. To further oppose the tendency of the winding drums, when freed from connection with the transmission gearing, to spin and uncoil its cable, additional means may be 50 employed, either with or without the means already described, which act against the cable directly. As an instance of such additional means there is here provided for retarding or opposing such spinning movement of the drum a device, the same herein comprising a friction or brake member 44 adapted to engage the periphery of the drum 13 when the latter is disengaged by 55 movement of the eccentric shaft and apply thereto a measure of frictional retardation.

Such brake member comprises a shoe 44, preferably faced with leather or other frictional material and suitably mounted to slide in the bracket 45. The shoe is pressed toward the drum by means of the spiral 70 spring 46, the pressure of which may be regulated by the adjusting screw 47. Preferably the shoe is so adjusted that, when the eccentric lever 32 is thrown to disengage the drum, the rim of the latter is brought 75 against the shoe, so that its tendency to rotate may be more or less retarded according to the compression of the spring 46. When the cable needs to be wound in by hand, the pressure of the shoe may be relieved to facilitate the winding-in operation. While one drum only is shown as provided with a drum-retarding device it is obvious that a similar attachment might be applied to the remaining drum.

By reference to Fig. 9 it will be seen that the machine is held in cut by the opposing pulls of the two cables exerted one near the wall end and the other near the opposite end of the machine. The sheave 15 therefore forms a fulcrum about which the machine may be swung to change its angular inclination by adjustably taking up or letting out the preceding cable 12.

In the illustrated machine I have provided means upon the machine itself for adjusting the cable 12, the same comprising means for turning the winding drum 16 more or less to tighten or loosen the cable. Any suitable means may be employed, but herein the same comprises ratchet and pawl mechanism for winding up the cable on the drum or unwinding the same therefrom to any desired extent. For this purpose there is mounted upon the machine frame a bracket 48 (Fig. 3) which carries the pivoted locking dog 49 adapted to engage the teeth of a ratchet wheel 50 fixedly secured to the drum 16. Engaging also with the teeth of the ratchet is the pawl 51, pivotally secured to the ratchet lever 45, the latter mounted to swing about the shaft 17. When the eccentric shaft 17 is turned to disengage the pinion 29 from the gear 30, the ratchet lever may be oscillated to ratchet 110 the winding drum around and thus adjustably take up, to any desired extent, the trailing cable 12. In order to maintain at the same time the established tension in the leading cable 11, means are preferably provided for preventing unwinding movement of the drum 13 during the ratcheting adjustment of the drum 16. Any suitable means may be employed, but herein there is provided (Fig. 1) upon the driving shaft 125 for the drum 13 a ratchet wheel 52 engaged by the pivoted detent or dog 53, which latter prevents unwinding movement of the drum 13. When it is required to wind the cable 11 on the drum 13 either by hand or 130

power the dog 53 may be thrown out of engagement with the ratchet wheel 52.

If it is required to slacken the drag line 12 to adjust the angular position of the machine, the dog 49 may be temporarily withdrawn from the ratchet wheel 50 and the latter allowed to turn under the control of the ratcheting lever 45 to any desired extent. For this purpose the dog 49 is provided with a lug 54 which may be pressed down to withdraw the dog from the ratchet. The dog is pressed into engagement with the ratchet by means of the spring 55, but when the drum is again thrown into engagement with the transmission gearing the dog is withdrawn from the ratchet either manually or automatically to leave the latter free to turn. To automatically withdraw the dog from the ratchet when the gear 30 is thrown into mesh with the shaft 28, the shaft 17 is provided with a finger 56 fixedly secured thereto. When the eccentric shaft 17 is turned by the lever 34 to connect the drum with the transmission gearing, the finger 56 is swung through approximately 180° with the shaft and caused to strike a laterally projecting lug 57 secured to the dog, and throwing the dog back about its pivot, automatically withdraws it from the ratchet. It therefore follows that the drag line may be taken in or let out and the position of the machine be regulated by the ratchet adjustment located on the machine itself. In order, however, to adjust the guiding means independently of the mechanism on the machine I may also employ preferably in connection with the drag line 12 a device apart from the said machine for taking in or letting out the cable. In the present instance (see Fig. 9) I have represented the fixed support 59 as consisting of an adjustable take-up jack of the type described in connection with the aforesaid patent to Mitchell, the same being more particularly shown as to its details in Figs. 16 and 17 of the said patent. The cable at its end is secured to a section of cable chain 58, which latter engages the take-up 59 so that, by adjusting the latter the cable 12 may be shortened or lengthened.

In Fig. 8 I have shown the arrangement of the cable 11 for effecting the starting or sumping cut. For this operation the cable is led forwardly about the sheave 15 and thence to a fixed jack or other support 59, the cable in this relation acting to draw the machine forward into the face of the coal prior to making the lateral or main cut.

In Fig. 9 I have shown the arrangement of the cables 11 and 12 when the machine is making its cut across the face. During this operation it will be noted that the cable 11 is connected to a fixed support 68, while the cable 12 is connected to the take-up 59, so that the machine may move transversely

across the face as the two drums 13 and 16 are operated, the movement of the machine being controlled by the controlling mechanism for those drums.

In Fig. 10 I have shown the arrangement of the machine for effecting a loading movement of the machine for the purpose of loading the latter upon a truck, or, as indicated in the drawings, upon a starting frame 60 such as is ordinarily employed to guide the machine in making the starting cut. While this may, if desired, be effected by one of the rope-winding drums previously described, herein there is provided a special power-driven member for effecting the loading movement, the same comprising the sprocket wheel 61 secured to the drum driving shaft 24 (see Fig. 1). When it is desired to draw the machine backward upon a truck or other member, such as the starting frame 60, a cable chain 62 is secured at 63 to the rear end of the frame and the opposite end passed about the sprocket wheel 60, so that the latter acts to draw in the chain and draw the machine upon the frame, the free end of the chain being held and taken in by the attendant.

In my improved construction wherein the drum 13 is disposed on a transverse horizontal axis, it will be noted that the machine is rendered exceedingly compact in its longest dimension so that it may work behind props relatively close to the face of the coal. At the same time, it is evident that it is possible to minimize the cable wear and the tangling effect of the back-lash on the feed cable when the feed is released, as, by the location of the drum at the side of the machine, it is possible to use a far larger drum than can be used on the front of the machine without damage to the roof. It will also be noted that during the cutting operation, the cable leading from the drum may pass directly to and around a guide

sheave 15, which is disposed in a plane tangent to the bottom of the drum, thus affording a direct and very efficient cable connection. As shown, a fixed sheave may also be used for either the sumping cut or the cut across the face, making possible the elimination of the cutting of the cable experienced with adjustable sheaves, which in practice have been found to be very difficult to maintain in position and very prone to swing out of place and thereby cause cutting of the cable. Attention is also directed to the fact that the drum 13, due to its improved location at the side of the machine, may also be so spaced relative to the sheave

as to insure correct winding of the cable on the drum. It should also be noted that by locating the drum 13 on the advancing side of the machine, the same may be very conveniently placed for the runner, whose normal position is at the left and rear of

the machine while it is making its cut from right to left, the several controlling mechanisms for the feed also being conveniently located for the runner when in that position.

So far as concerns the drag line drum 16 from which the drag line extends laterally at the rear of the machine, attention is also directed to the fact that by extending the 10 drag line laterally from the point indicated, the machine is correctly balanced, the cables passing out from the machine at such points relative to its length as to maintain the correct balance thereof in all cuttings and render the use of a double strand of cable in hard cutting unnecessary. Through the provision of an adjustable brake control for the drum, the drag line 12 may also be so controlled by the operator as to adjust the 20 angle at which the cutter bar 2 operates upon the coal and thus keep the latter in the position for most effective cutting. It will also be noted that through the provision of the ratchet mechanism the operator is enabled to adjust the drag line against a considerable tension, this being a feature of distinct value as it enables the squaring up of the machine at the end of the cut across the face. It will, however, be understood that 30 the advantages to be obtained by the use of this drag line drum and its controlling mechanism are not obtainable solely from a drum located at the rear of the machine as shown, but that the same are obtainable wherever the drum is located, so long as 35 the cable extends laterally from the rear of the machine or my improved means for controlling the drum are used.

While I have herein shown for the purpose of illustration one specific form of my invention, it is to be understood that the same is not limited to the details of construction, or the relative arrangement of parts, or the application herein made of the 40 invention, or the particular form of mining machine shown, but that extensive deviations may be made in respect to these features from the showing made without departing from the spirit of the invention.

Having thus described my invention what I claim is:

1. A mining machine comprising, in combination, a main body portion having a cutter bar projecting from one end thereof, a power driven winding drum having an axis extending transversely relative to the longitudinal axis of said machine, a guiding member adjacent the wall end of said body portion, and a flexible feeding and guiding element passing from a fixed support in advance of the machine around said guiding member to said winding drum.

2. A mining machine comprising a body portion, cutting mechanism projecting therefrom, a power driven winding drum on the

advance side of said body portion and having an axis extending transversely relative to the longitudinal axis of said machine, a guiding member adjacent the wall end of said body portion and on the advance side thereof, and a flexible feeding and guiding element passing from a fixed support in advance of the machine around said guiding member to said winding drum.

3. A mining machine comprising, in combination, a body portion, cutting mechanism projecting therefrom, a power driven winding drum having an axis extending transversely relative to the longitudinal axis of said machine, a guiding sheave disposed in a plane substantially tangential to said drum and adjacent the wall end of said body portion, and a flexible feeding and guiding element passing from a fixed support in advance of the machine around said guiding sheave to said winding drum.

4. A mining machine comprising, in combination, a main body portion having a cutter bar projecting from one end thereof, a power driven winding drum having an axis extending in a generally horizontal direction transverse to the longitudinal axis of said machine, a guiding sheave disposed in a plane tangential to said drum adjacent the wall end of said body portion and on the advancing side thereof, and a flexible feeding and guiding element passing from a fixed support in advance of the machine around said sheave to said winding drum.

5. A mining machine comprising, in combination, a main body portion having a cutter bar projecting from one end thereof, a power driven winding drum overhanging the advance side of said body portion and disposed in a generally longitudinal direction, a guiding member adjacent the wall end of said body portion and on the advance side thereof, and a flexible guiding element passing from a fixed support in advance of the machine around said guiding member to said winding drum.

6. A mining machine comprising a body portion, cutting mechanism projecting therefrom, a power driven shaft having its axis extending transversely relative to the longitudinal axis of said machine, a pinion on said shaft, a winding drum at one side of said body portion having an internal gear driven by said pinion, a guiding member adjacent the wall end of said body portion, and a flexible feeding and guiding element passing from a fixed support in advance of the machine around said guiding member to said winding drum.

7. A mining machine comprising, in combination, a body portion, cutting mechanism projecting therefrom, a power driven winding drum on said body portion and having an axis extending in a generally horizontal direction transverse to the longitudinal axis

of said machine, a flexible advance feeding and guiding element extending from said winding drum to a fixed support in advance of the machine, a drag line drum carried by said body portion, and a drag line connecting said drag line drum with a fixed support in the rear of said machine.

8. A mining machine comprising, in combination, a main body portion having a cutter bar projecting from one end thereof, a power driven winding drum on the advance side of said body portion and having an axis extending in a generally horizontal direction transverse to the longitudinal axis 15 of said machine, a flexible advance feeding and guiding element extending from said winding drum to a fixed support in advance of the machine, a drag line drum carried by said body portion, and a drag line connecting said drag line drum with a fixed support in the rear of said machine.

9. A mining machine comprising, in combination, a main body portion having a cutter bar projecting from one end thereof, a power driven winding drum on the advance side of said body portion and having an axis extending in a generally horizontal direction transverse to the longitudinal axis of said machine, a flexible advance feeding and 30 guiding element extending from said winding drum to a fixed support in advance of the machine, a drag line drum carried by said body portion, a drag line connecting said drag line drum with a fixed support in 35 the rear of said machine, and manually controlled braking means for one of said drums.

10. A mining machine comprising, in combination, a main body portion having a cutter bar projecting from one end thereof, a power driven winding drum on the advance side of said body portion and having an axis extending in a generally horizontal direction transverse to the longitudinal axis 45 of said machine, a flexible advance feeding and guiding element extending from said winding drum to a fixed support in advance of the machine, a drag line drum carried by said body portion, a drag line connecting said drag line drum with a fixed support in 50 the rear of said machine, and manually controlled braking means for one of said drums operable at any time during the operation of the machine.

55 11. A mining machine comprising, in combination, a main body portion having a cutter bar projecting from one end thereof, a power driven winding drum on the advance side of said body portion and having an 60 axis extending in a generally horizontal direction transverse to the longitudinal axis of said machine, a flexible advance feeding and guiding element extending from said winding drum to a fixed support in advance 65 of the machine, a drag line drum carried by

said body portion, a drag line connecting said drag line drum with a fixed support in the rear of said machine, and ratchet means for rotating said drag line drum to wind in said drag line.

12. A mining machine comprising, in combination, a body portion, cutting mechanism projecting therefrom, a power driven winding drum on said body portion having an axis extending in a generally horizontal 70 direction transverse to the longitudinal axis of said machine, a flexible advance feeding and guiding element extending from said winding drum to a fixed support in advance of the machine, a drag line drum carried by 75 said body portion, a drag line connecting said drag line drum with a fixed support in the rear of said machine, manually controlled braking means for one of said drums, and ratchet means for rotating said drag line drum to wind in said drag line.

13. A mining machine comprising, in combination, a main body portion having a cutter bar projecting from one end thereof and rigidly attached thereto, an actuator, a flexible advance feeding and guiding member leaving the machine at a point adjacent the wall end of said body portion, a rearwardly extending flexible drag line member leaving the machine at a point removed 95 from the wall end of said body portion, a drum for each of said flexible members, the drum for said advance feeding and guiding member being located on the advance side of said body portion and having an axis extending in a generally horizontal direction transverse to the longitudinal axis of said machine, and a driving connection between said actuator and said drum for said advance feeding and guiding member.

14. A mining machine comprising, in combination a main body portion having a cutter bar projecting from one end thereof and rigidly attached thereto, an actuator, a flexible advance feeding and guiding member leaving the machine at a point adjacent the wall end of said body portion, a rearwardly extending flexible drag line member leaving the machine at a point removed from the wall end of said body portion, a drum for each of said flexible members, the drum for said advance feeding and guiding member being located on the advance side of said body portion and having an axis extending in a generally horizontal direction transverse to the longitudinal axis of said machine, and a driving connection between said actuator and each of said drums.

15. In a mining machine, the combination with cutting mechanism, of guiding means comprising a pair of flexible guiding members connected each to a fixed support, one on the advancing side of the machine and the other on the receding side thereof, said guiding means being connected to the ma- 120 125 130

chine, one relatively near the wall or cutting end and the other nearer the opposite end thereof, a pair of power-driven members connected to move in unison and engaging each of said guiding members and acting to draw in one while paying out the other, means at will to cause either of said power-driven members to be moved and disconnected from the other, and means rendered effective by such movement of said

drum to prevent sudden uncoiling movement thereof.

In testimony whereof, I have signed my name to this specification in the presence of two subscribing witnesses.

ALBERT BALL.
